UNITED STATES PATENT OFFICE

156,219

DESIGN FOR A BOTTLE

Donald Deskey, New York, N. Y., assignor to The Procter & Gamble Company, Cincinnati, Ohio, a corporation of Ohio

Application November 26, 1948, Serial No. 149,839

Term of patent 14 years

(Cl. D58—6)

To all whom it may concern:

Be it known that I, Donald Deskey, a citizen of the United States, residing at New York, in the county of New York and State of New York, have invented a new, original, and ornamental Design for a Bottle, of which the following is a full, clear and exact description, reference being had to the accompanying drawings, forming a part thereof.

I claim:

The ornamental design for a bottle, substantially as shown.

DONALD DESKEY.
